UNITED STATES PATENT OFFICE.

WILLIAM J. CONNORS, OF SAN JOSE, CALIFORNIA.

ADJUSTABLE WINDOW SASH.

Application filed April 18, 1927. Serial No. 184,551.

This invention relates to improvements in sash window construction, the principal object being to provide a sheet or pressed metal sash structure adapted to be fitted into a standard wooden frame and provided with adjustment means to enable the sash to fit properly into the frame regardless of the variation in width of the frames which is found at times due to the materials and the method of construction employed in making such frames.

I have particularly in mind to arrange my adjustable sash in connection with a combination sash and casement window structure, such as is shown in my copending application for patent, Serial No. 168,331, filed February 15th, 1927, so as to enable this improved window structure to be installed in the wooden frames of buildings already erected and provided with such frames. By means of the adjustment feature the window structure may be properly fitted into the frames regardless of whether any discrepancy in the dimensions of the frames is found and without any cutting away or alteration of the frames being necessary.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is an interior elevation of my improved window structure as mounted in connection with a wooden frame, the lower sash being partly broken out to show the adjustment feature.

Fig. 2 is an enlarged fragmentary view of one of the sliding sashes showing the cooperating adjustment plate member disengaged therefrom.

Fig. 3 is a cross section of the sash and the adjustment plate.

Fig. 4 is a fragmentary vertical section on the line 4—4 of Fig. 3.

Referring now more particularly to the characters of reference on the drawings, each sliding sash 1 comprises a rectangular metal member of hollow box like section, as is customary in the construction of pressed metal sashes. Each sash is adapted to receive a

casement sash 2, in which the window pane 3 is mounted and which is hinged onto one side of the outer sliding sash as at 4 for inward swinging and opening movement. The inner periphery of the sash 1 is provided with an inwardly projecting flange 5 and with a groove 6 inwardly of said flange. The sash 2 fits against the flange 5, while the groove serves as a water catch and drain means as 65 featured in said copending application. This feature, however, has nothing to do with the present invention.

The outer vertical edge of the sash 1 on the side thereof opposite to the hinge 4 is 70 open from top to bottom as shown in Fig. 2, thus forming a deep wide groove between the sides of said sash. A vertical plate 7 having side flanges 8 fits into said groove, the flanges having close engagement with the inner surfaces of the sash-sides. At top and bottom the plate 7 is provided with horizontal ears 9 overhanging and extending beyond the flanges 8, the opposite faces of said ears being adapted to rest against the outer faces of 75 cups 10 depressed in the metal of the outer horizontal edge faces of the sash. The ears have holes 11 therethrough with nuts 12 welded on the adjacent faces of the ears concentric with said holes. The cups are of a size sufficient to receive the heads 13 of screws or bolts 14 which are threaded into the nuts, the cups being slotted longitudinally as at 15, so as to permit of a certain adjustment of the plate member to and from 80 the adjacent transverse edge of the sash. The plate 7 from its upper end downwardly a certain distance has a vertical groove or depression 16 of suitable width and depth to receive one end of the usual counter-weight 95 cord 17 therein, said cord passing through a hole in the metal at the bottom and back of the groove and being knotted beyond said hole as shown in Fig. 1.

It is assumed that the width of the fixed or permanent portions of the metal sash is such that said sash will fit the smallest wood frame of a certain standard size liable to be encountered. It will therefore be seen that if undue space is found to exist between the transverse edges of the sash 1 and the vertical members of a wooden frame 18 in which it is desired to install the sashes, it is only necessary to loosen the screws 14, slide the plate 7 outwardly the necessary distance, and again tighten the screws. This tightening of the screws of course acts to clamp the ears against

the adjacent surfaces of the cups so as to hold said plate member then immovable. The metal of which the sash is made is so thin that the slight offset between the edges of the 5 sash and the flanges 8 of the plate member will not be noticed even if such offset is disposed so that it is not concealed by the guide beading of the frame.

From the foregoing description it will be 10 readily seen that I have produced such a device as substantially fulfills the objects of the invention as set forth herein.

While this specification sets forth in detail 15 the present and preferred construction of the device, still in practice such deviations from such detail may be resorted to as do not form a departure from the spirit of the invention, as defined by the appended claims.

Having thus described my invention what 20 I claim as new and useful and desire to secure by Letters Patent is:

1. In window construction, a sash, one vertical outer edge of which is grooved for substantially the entire transverse extent of the 25 sash, a plate member having side flanges projecting into the groove for horizontal movement to and from the adjacent edge of the sash, horizontal ears on the top and bottom of the plate member to engage the corresponding surfaces of the sash, and adjustment means securing the ears to the sash.

2. In window construction, a sash, one vertical outer edge of which is grooved for substantially the entire transverse extent of the sash, a plate member having side flanges projecting into the groove for horizontal movement to and from the adjacent edge of the sash, horizontal ears on the top and bottom of the plate member to engage the corresponding surfaces of the sash, openings 35 through each ear and the corresponding sash-surface, one of said openings being slotted, and a clamping belt through said openings.

3. In window construction, a hollow sash, one vertical edge of which is cut away from 40 top to bottom for the full width between the sides of the sash, a plate member having side flanges to project between and engage said sides, horizontal ears on the top and bottom of the plate to extend toward the sash, and 45 provided with tapped orifices; opposed cups depressed in the top and bottom surfaces of the sash adjacent the cut away edge to receive screwheads from above and below the sash; the ears being adapted to rest on the 50 adjacent outer faces of the cups, the latter having slots through the bottoms thereof and screws through said slots threaded into the nuts.

In testimony whereof I affix my signature.

WILLIAM J. CONNORS.
